FLAPPING WING TOY

William Eugene Polk, Shreveport, La.

Application June 23, 1949, Serial No. 100,810

1 Claim. (Cl. 46—124)

1

This invention relates to a toy, and more particularly to a manually operable toy.

The object of the invention is to provide a manually operable toy which may be shaped to represent a bat, butterfly, bird, or other object, the present invention including a pair of wing sections that are adapted to be manually oscillated or moved whereby the toy of the present invention will simulate a bird, butterfly, or the like, in flight.

Another object of the invention is to provide a fanciful toy which is constructed so that the operating mechanism for the toy can be readily attached to and detached from the wing sections, the wing sections adapted to be made of sheet material so that a plurality of the wing sections can be stamped out of suitable material at one time.

A further object of the invention is to provide a mechanical toy which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a top plan view of the toy of the present invention.

Figure 2 is a sectional view taken on the line 2—2 of Figure 1.

Figure 3 is a sectional view taken on the line 3—3 of Figure 1, and showing the wing sections in a different position.

Figure 4 is a plan view showing the wing sections disassembled.

Figure 5 is a plan view of the arms of the operating mechanism.

Figure 6 is an end elevational view of the arms of the operating mechanism.

Figure 7 is a sectional view taken on the line 7—7 of Figure 1.

Figure 8 is a sectional view taken on the line 8—8 of Figure 1.

Figure 9 is a perspective view of one of the arms.

Referring in detail to the drawings, there is shown a toy which includes a pair of similar wing sections 10 which are fabricated of suitable sheet material. The wing sections 10 may be shaped to resemble the wings of a butterfly, bird, or other fanciful object, and each of the wing sections is provided with a slot 11. It will be seen that with the wing sections 10 in their

2

assembled positions, each wing section is positioned or engages the slot in the other wing section.

Each of the slots 11 has its inner end terminating in an enlarged cut-out 12, Figure 4. Each of the wing sections 10 comprises an upper wing portion 14 and a lower cover portion 15, there being a body section 16 provided in each of the wing sections. It will be seen that the cut-outs 10 12 are arranged in the body sections 16.

The wing sections 10 are further provided with a plurality of apertures or openings 17, and suitable cords or flexible lines 18 extend through the apertures 17 for connecting the wing sections 10 together.

A manually operable means is provided for oscillating or moving the wing sections 10, and this means comprises a strip 19 which is secured to each of the wing sections 10 by suitable securing elements 21. Each of the strips 19 is provided with an offset portion 20 which defines a pocket for a purpose to be later described.

The operating mechanism for reciprocating or oscillating the wing sections 10 comprises a pair of arms 22 which extend through the cut-outs 12. Each of the arms 22 is provided with a flat portion 23 which is snugly received within the pocket 20, and further, each of the arms 22 is provided with a finger-engaging loop 24 which is adapted to be engaged by the user's fingers for oscillating the wing sections 10. The arms 22 further include an arcuate section 26 which is arranged contiguous to a sleeve or bushing 25, and a suitable pivot pin 27 extends through the bushings or curved portions 25 for pivotally connecting the pair of arms 22 together.

From the foregoing, it is apparent that a toy has been provided which includes the wing sections 10 that are adapted to be oscillated by means of the arms 22. The operating arms 22 may be readily attached to or detached from the wing sections and the wing sections are constructed so that the major portion of the arms is covered by the wing sections. The wing sections may be made of sheet material so that a plurality of these parts may be stamped out in one operation. If desired, cellulose acetate of any desired color can be used for making the wing sections and the cellulose acetate will provide flexibility, strength, and ease of fabricating. However, other materials may also be used. The body sections 16 can be shaped to simulate the head and tail of the bird or butterfly or other object, and the cords 18 may be catgut or other suitable material. By means of the pockets 20,

various operating arms and wing sections can be interchangeably used with each other. Also, various types of padding or decorative material can be applied to the wing sections as desired.

I claim:

In a toy, a pair of wing sections fabricated of sheet material and each provided with a slot, the slot in one of said wing sections extending rearwardly from an edge therein, and the slot in the other wing section extending forwardly from an edge whereby with the wing sections in their assembled position, each wing is positioned in the slot of the other wing, each of said slots having its inner end terminating in an enlarged cut-out, said wing sections each comprising an upper wing portion, a lower cover portion and a body section, said cut-out being positioned in said body section, there being a plurality of apertures in each of said wing sections, cords extending through said apertures for connecting said wing sections together, a strip secured to each of said wing sections and provided with an off-

set portion defining a pocket, an operating mechanism for reciprocating said wing sections, said operating mechanism comprising a pair of arms extending through said cut-outs and pivotally connected together therein, an end of each of said arms being seated in said pockets, and a finger-engaging loop arranged on the other end of each of said arms.

WILLIAM EUGENE POLK.
